UNITED STATES PATENT OFFICE.

EDGAR KNIGHT, OF NEW YORK, N. Y., ASSIGNOR OF ONE-HALF TO WILLIAM REYNOLDS AND AMOS W. BUTLER, OF BROOKVILLE, INDIANA.

KNOB-LATCH.

SPECIFICATION forming part of Letters Patent No. 340,048, dated April 13, 1886.

Application filed May 5, 1885. Serial No. 164,441. (No model.)

To all whom it may concern:

Be it known that I, EDGAR KNIGHT, of the city, county, and State of New York, and a citizen of the United States, have invented a new and useful Improvement in Knob-Latches, of which the following is a full, clear, and exact description, reference being had to the accompanying drawings, forming part of this specification.

10 My invention relates to a knob-latch; and it consists in the devices and their combinations, hereinafter particularly described, and as recited in the claims.

Figure 1 is a side elevation of a portion of a door-stile, showing my improved latch in dotted lines seated therein. Fig. 2 is a horizontal sectional view of the style and knob-latch therein, disclosing the operative mechanism. Fig. 3 is a vertical central section of the latch-case and face-plate, and showing the bolt and its spring in full lines. Fig. 4 is an inner face view of the face-plate detached from the case; and Fig. 5 is a vertical cross-section of the case, the bolt, and the operating-pinion on the 25 line of the axis of the latter, the case being united to the face-plate.

A is the case. This is cylindrical in form, as shown, and may be formed of a piece of metal tubing. The edge of the rearward or 30 bottom end is preferably turned inwardly, as at a, to form an annular shoulder, against which rests a disk, a', whereby this end of the case is effectively and economically closed.

B is the face-plate having on its rearward 35 side the circular boss b, which is adapted to fit into the forward end of the case. The interior face of the wall of the case at this end is screw-threaded, as at b', and the boss is exteriorly threaded to correspond, whereby the 40 face-plate may be secured to the case by screwing the boss b into the end of the case, as shown in Figs. 2 and 3. The face-plate has the bolt-slot b², located centrally of the screw-boss, through which the bolt is shot.

45 C is the bolt, shown with the usual bevel latch end, c, fitted to move in slot b² in the face-plate. The body of the bolt has the transverse and interiorly-located slot c', from one of the walls of which and projecting inwardly of the 50 bolt is the rack c². At the opposite ends of the slotted bolt-body are the annular or cylindrical

bearings c³ and c⁴, which fit loosely against the interior of the case. The bearing c³ on its forward face is shouldered at c⁵ to abut against the base of the screw-boss b, and thus act to 55 limit the forward throw of the bolt, while between the outward or rear face, c⁴, and the end plate, a', of the case is the spring D, seated in the case and having bearings against c⁴ and a', as shown.

60 At E is shown the actuating pinion carried by the spindle f. This pinion engages the rack c² on the interior of the bolt-body, as shown, and is operated to retract the bolt by throwing it rearwardly of the case and compressing the spring D. When the pinion is released, the spring D obviously shoots the bolt forward. The pinion is formed with the hubs e and e'—one on each side—and these hubs are respectively shouldered at e² and e³ 65 to constitute bearings, one of which enters a slot, a², in the case, and the other of which fits into a slot in a cap, a³, which is screwed into the slot a⁴ in the opposite wall of the case. The slot a⁴ in the case is large enough to admit 70 the passage of the largest diameter of the pinion, so that the devices may be easily put together, and the cap a³ is countersunk in the face of the case, so that the parts when adjusted will enable the case to present a smooth 75 cylindrical exterior.

The devices, as shown, are put together by first introducing the plate a' into the forward end of the case and dropping it flatwise against the turned edge a. The spring D is then put 80 in the case and is followed by the bolt, and the face-plate is then screwed into its seat. The pinion is then introduced into the case through the side slot, a⁴, and its hub e is seated in slot a², when the screw-cap a³ is placed in its seat, 85 its central slot constituting the other bearing of the pinion. The spindle f is now capable of being passed through the angular slot longitudinal of the pinion, and one or more knobs, 90 F, may then be attached to the spindle in the 95 usual way.

My described knob-latch device is peculiarly adapted to be seated readily and speedily in door-strokes and similar places.

In placing the latch in a door-stile the workman has only to use an auger to form a cylindrical recess in the stile of a bore adapted to

receive and fit snugly to the lock-case, to cut a shallow recess to receive the face-plate, and to bore a hole transverse the stile on the axial line of the pinion for the passage and seating 5 of the spindle. The time and labor involved in the cutting of a deep rectangular recess in the stile, as is demanded for ordinary lock and latch cases, is avoided.

My latch as described is economical in 10 structure, simple in mechanism, and effective and durable in application.

It is obvious that the described mechanism for operating the latch may be combined with and used in a case which is angular in cross- 15 section in place of being cylindrical, as set forth.

What I claim as my invention, and desire to secure by Letters Patent, is—

1. In a knob-latch, the combination, with 20 the inclosing-case and face-plate, of the latch-bolt slotted at c' and having the inwardly-projecting rack c' , and the shoulder-bearings c^3 and c^4 , engaging the wall of the case, the spring D, and the pinion E, having hubs e and e' , having bearings in the case and longitudinally slotted to receive the knob-spindle f , substantially as described, and for the purpose 25 set forth.

2. In a knob-latch, the combination, with 30 the case inclosing the operating mechanism, and having the interior of the wall at its forward end threaded, of a face-plate provided with a threaded boss on its rearward face, whereby the face-plate may be screwed into and thus seated upon the end of the case, as 35 specified.

3. The combination, with the latch-bolt C, 40 its slot c' , rack c' , bearings c^3 and c^4 , and pinion E, of spring D, and inclosing-case A, provided with face-plate B and inwardly-turned rearward edges a and disk or end plate, a' , as and for the purpose set forth.

4. The combination, in a knob-latch, with 45 the bolt C, having a transverse slot, c' , in which is the inwardly-projecting rack c' , the operating-pinion E, having hubs e and e' , and the spring D, of the inclosing-case A, having the slots a^2 and a^4 , and the screw-cap a' , together with the face-plate B, as and for the purpose specified.

EDGAR KNIGHT.
